UNITED STATES PATENT OFFICE.

CHARLES W. RENNER, OF ALTOONA, PENNSYLVANIA.

WEATHER-STRIP.

1,111,548.

Specification of Letters Patent. Patented Sept. 22, 1914.

Application filed March 6, 1912. Serial No. 681,909.

To all whom it may concern:

Be it known that I, CHARLES W. RENNER, a citizen of the United States, residing in Altoona, in the county of Blair and State of Pennsylvania, have invented a certain new and useful Improvement in Weather-Strips, of which the following is a true and exact description, reference being had to the accompanying drawings, which form a part 10 thereof.

My invention consists in a novel weather strip construction primarily devised to secure a tight joint between the top of a vertically sliding window sash and its casing in a 15 steel railway passenger car.

The various features of construction and arrangement which characterize my invention are pointed out with particularity in claims annexed to and forming a part of 20 this specification. For a better understanding of my invention, however, and the advantages possessed by it reference should be had to the accompanying drawings and descriptive matter in which I have illustrated 25 and described one form in which my invention may be embodied.

Of the drawings: Figure 1 is a partial side elevation of a steel passenger car. Fig. 2 is a section on the line 2—2 of Fig. 1. Fig. 30 3 is a perspective view of a portion of one of the weather strip parts shown in Fig. 2. Fig. 4 is a perspective view of a portion of a second weather strip part shown in Fig. 2.

In the drawings, A represents a vertically 35 sliding window sash working in a casing comprising metal posts B, a metal top piece C, and a metal sill D. As shown the sash frame is made of wood.

The weather strips for securing a tight 40 joint between the top of the window sash A and the casing top pieces C comprise co-operating parts secured to the top of the window sash and to the inturned horizontal flange C' of the casing top piece C. The 45 part E secured to the window sash is a metal strip E. The strip E is formed with a flat horizontal body portion bearing against the sash and an extension E' which overlaps the casing frame D' and is trough shaped with 50 its convex side up. At the free edge the trough shaped extension E' terminates advantageously in a rounded bead E''. At its inner edge the strip E terminates in a down turned flange E''' entering a vertical groove 55 formed for the purpose in the window sash.

The strip E is secured to the window sash by screws F. A metal clamping strip G is shown as interposed between the heads of the screws F and the body of the strip E. Advantageously as shown the sash may be 60 recessed so that the top surface of the strip G is flush with the upper edge of the window sash. To the flange C' of the casing part C is secured a metal strip H having a horizontal body portion resting against the 65 upper side of the flange C'. The strip H also comprises an inclined flange portion H' which terminates at its upper end in a hollow bead H''. The outer surface of the bead H'' is partly covered by the fabric I. As 70 shown the cloth I is stitched at I² to form a hem or doubled portion I' receiving a metal rod or wire J which is axially inserted in the hollow bead H''. The cloth I extends out of the bead H'' through the space left 75 between the edge H³ and the body of the flange H' and passes over the upper side of the hollow bead H'', down along the upper side of the inclined flange portion H', and under the body of the strip, being secured 80 with the latter to the casing flange C' by screws G' placed upward through the flange C' and threaded into the metal clamping strip G bearing against the upper side of 85 the body of the strip H. The body of the strip E may be notched at its ends, as indicated at E⁴, in order to clear a weather strip or guide which may be secured to the side portions of the window casing.

The strips E and H are formed of 90 resilient metal, preferably in practice of spring brass. The cloth I may be any suitable cloth of sufficient durability and thickness. Billiard cloth forms a very satisfactory material for this purpose, but excellent results may 95 be obtained with less expensive fabrics. The parts are so proportioned that when the window is closed the cloth covered bead H'' fits snugly in the trough shaped flange E' and both the latter and the flange H' are flexed 100 somewhat to give the desirable contact pressure. With the construction shown it will be obvious that it is easy to draw the cloth I taut and to replace the cloth from time to time when this becomes necessary or desirable. As the metal strips E and H are both 105 of resilient metal and both have their contacting portions free at one edge, they have a considerable capacity for movement to compensate for any irregularity in the adjusting 110

or proportioning in the sash and window casing, while at the same time engaging with the desired pressure when the sash is closed. The cloth interposed between the metal strips 5 in the manner described insures a very desirable seal highly effective in excluding air, dust snow or moisture under the severe conditions met with in the operation of steel railway cars.

10 I have not thought it necessary to illustrate or describe in detail herein any of the provisions made for sealing the joints between the sides and bottom of the window sash and the corresponding casing portions 15 as these features form no part of my present invention. A construction suitable for such purpose is shown however, in my prior application, Serial No. 607,899, filed February 11, 1911.

20 While in accordance with the provisions of the statutes I have illustrated and described the best form of my invention now known to me, it will be apparent to those skilled in the art that changes will be made 25 in the form of the apparatus disclosed without departing from the spirit of my invention and that under some circumstances certain features of the invention may be used with advantage without a corresponding use 30 of other features.

Having now described my invention what I claim is new and desire to secure by Letters Patent is:

1. A weather strip consisting of a strip

of resilient metal comprising a body portion 35 adapted to be clamped to the object to which the strip is to be applied and an extension thereof terminating at its free edge in a hollow bead open at one side, a sheet of fabric entering said hollow bead through 40 said open side and passing over the convex surface of said bead and alongside of said body portion and clamped between it and the object to which the strip is applied and a member axially inserted in said hollow bead 45 and engaging the portions of the fabric portion entering the bead to secure said metal and fabric strips together.

2. A weather strip consisting of a strip of resilient metal comprising a body portion 50 adapted to be clamped to the object to which the strip is to be applied and an extension thereof terminating at its free edge in a hollow bead open at one side, a sheet of fabric formed with a loop entering said hollow bead through said open side and passing over the convex surface of said bead and alongside of said body portion and clamped between it and the object to which the strip is applied and a rod axially inserted in said hollow bead and in the loop of said fabric to thereby secure said metal strip and fabric sheet together.

CHARLES W. RENNER.
